AID FOR PIERCED EARS

Kenneth L. Roberts, Alexandria, Va.

Application October 17, 1952, Serial No. 315,348

6 Claims. (Cl. 128—329)

This invention deals with ear rings for ornamental use and deals particularly with a special ring for a freshly pierced ear. Such a ring facilitates development of a proper opening through the ear lobe.

Providing suitably pierced openings through ears for ear rings has been regarded oftentimes as a cursory task. Often it is accomplished with a simple needle; then later when the perforation is healed, various sorts of ear ornaments are hung from the ear. There has been little thought toward exact placement of the perforation so that a given ornament will hang to best advantage or so that ornaments in both ears will appear symmetrical. Nevertheless, fashion demands such appearance as reflects careful preparation of the pierced ear. Some ear ornaments are a pendent type, hanging from a loop through the opening in the ear lobe. Some ear ornaments are a stud type, held against the lobe by a shaft through the lobe opening. Each type imposes its own detailed requirements, but each requires the size of the opening pierced through the ear lobe to be of the same order as the loop or the shaft to be retained. If the opening is too small, clearly the ornament cannot be worn. If the opening is too large, then the ornament easily shifts out of position so as to attract unfavorable attention even from a casual observer. Other aspects of the problems will appear, on analysis, confronting the wearer of pierced ear ornaments.

One difficulty to which this invention is directed stems from the physiological situation that arises when an ear lobe is pierced. There is, of course, first the sanitary requirement. Whatever means of piercing is used should be easily sterilized. But more than that, sanitary conditions must prevail as the ear is healing. Moreover, as the ear heals, the opening if left alone tends to grow together. The opening should be kept from filling in by growth; especially should be kept to just the size intended for given ear ornaments. Further, the opening should be kept at the exact spot and aligned across the lobe in just the exact direction as when first pierced. Haphazard fittings in the opening during the healing stage leads to small changes that later are magnified in untidy hanging of the ear ornament. It is especially important for the hole to heal to proper size for the intended fastening. Other problems and requirements will appear in further description of this invention.

Specific illustration of this invention appears in the accompanying drawings and various novel features thereof are set forth in the appended claims.

In the drawings:

Fig. 1 shows a tapered ring of this invention as carried by a pierced ear lobe.

Fig. 2 shows a section through the lobe of an ear, along the line 2—2 of Fig. 1, with a special ring of this invention through the lobe. Fig. 3 shows a modified form of tapered ring of this invention having a portion modified to afford a means of fastening and also other functions.

Fig. 4 shows a ring such as that of Fig. 3 but in closed position, showing a portion broken away to exhibit a particular fastening.

2

Fig. 5 shows another modification of this invention having fastening means functioning also to retain a pulling element such as wire or thread.

Advantages of this invention become apparent in various specific embodiments in which the piercing through an ear lobe is supplemented by a special ring. This ring tapers in cross-section. The ring may remain open but preferably comprises elements adapted to lock the ring. The ring is of size and material to be worn in a pierced ear, as will appear more fully in this description. The taper of the ring serves to control the set or the size of the freshly-pierced opening as it heals.

This invention is illustrated in specific form by reference to the drawings.

When an ear lobe is pierced, the ring 1 is inserted immediately in the piercing. This is shown in Figs. 1 and 2. Fig. 2 shows ring 1 through an ear lobe as in cross-section 2—2 of Fig. 1. Any suitable additional ear ornament 2 may be carried on ring 1, so that the ring might be termed a fastening for ornament 2; but the ornament may be omitted. However, it is clear that the material of ring 1 is of the order of magnitude of an ear ring fastening and tapers around the ring. Since ring 1 is an open ring, one end may be termed a small end and the other a large end.

When ring 1 is inserted through the fresh piercing of an ear lobe, the ring is drawn around gradually filling the opening more and more until the opening is filled to any desired size within the limits of the taper of ring. With ring 1 left at the selected position, the opening is kept to the corresponding size during healing so that finally the ear piercing is formed as a clean opening of the selected size. A particular advantage is that during healing the opening remains clean and does not require attention, as contrasted with the situation where old material is removed and new material inserted. Such has been the case where, for example, a thread is left in the piercing end then moved at intervals. Such former practice was not sanitary.

Though ring 1 may be left as an open ring, it may be desired to close the ring. To this purpose one end contains an opening to be engaged or latched with the other end. Preferably an opening 3 is provided transversely through larger end 4, as shown in the partial section in Fig. 3. A suitable latching arrangement is shown in Figs. 2 and 4. Here the smaller end 5 is bent near its juncture with the body of the ring to form something of a hook or catch suitable to engage in opening 3 and hold the ring closed. Fig. 4 shows such arrangement. Other specific forms may be provided to hold the ring closed.

Other features of this structure are illustrated also in the drawings. In Fig. 3 the small end of ring 1 is bent out into hook or catch form 5 and then extends out from the body of the ring to terminate in a needle point 6. With this modification, the ring serves to facilitate moving a needle to pierce an ear lobe and in turn the needle serves to facilitate drawing the ring immediately into the opening through the lobe. Then the needle end may be severed from the body of the ring, leaving the out-turned hook 5 ready to catch in the other end of the open ring. The ring material, tapering as it does, is then moved to fill the fresh opening to desired size during healing. In some cases the extension 6, though of the same form as this needle shown in Fig. 3, may be of more pliable material, for example of wire. In this case the tip 6 may be inserted through the eye of a piercing needle and bent to be held thereby. Thus this extension and then the ring are drawn by the needle through the freshly pierced opening.

Another modification of this invention is shown in Fig. 5. Here the small end of ring 1 contains an opening 7 in the nature of an eye to receive thread 8. This is

shown in the partial section in Fig. 5. Thus, a needle with thread serves to pull the small end of ring 1 through the piercing of a lobe. The ring is then closed and adjusted in the fresh opening as already described. In this form also, ring 1 serves various functions.

It will be clear that in some instances a person may use the tapered ring of this invention to enlarge a lobe piercing made some time previously; that is, a previously existing opening after it has healed.

It will be clear to those skilled in this art that various alterations and departures from those specific forms may be made in this invention. But in accordance with the Patent Statutes, the preferred forms and modes of operation of this invention have been illustrated. Novel features of this invention are set forth in the appended claims.

What is claimed is:

1. Means to facilitate forming an ear lobe piercing to desired size, comprising a ring, the material of which is of size of the order of magnitude of an ear ring fastening and tapers around the ring from one end to the other, the ring being broken, the smaller end being formed as an extension from the ring to facilitate its own insertion and that of the ring through an ear lobe piercing, whereby the piercing may be filled by appropriate part of the ring to any desired size during healing.

2. Means to facilitate forming an ear lobe piercing to desired size comprising an open ring, the material of which is of size of the order of magnitude of an ear ring fastening and tapers around the ring from one end to the other, the ring being broken, the smaller end being formed as an extension from the ring to facilitate its own insertion and that of the ring through an ear lobe piercing, the ends being formed to engage each other directly in a fastening to close the ring, whereby the piercing may be filled by appropriate part of the ring to any desired size during healing.

3. Means to facilitate forming an ear lobe piercing to desired size comprising an open ring, the material of which is of size of the order of magnitude of an ear ring fastening and tapers around the ring uniformly throughout, the larger end being perforated and the smaller end being hooked to engage the perforation on closing of the ring, whereby the piercing may be filled by appropriate part of the ring to any desired size during healing.

4. Means to facilitate forming an ear lobe piercing to desired size comprising an open ring, the material of

which is of size of the order of magnitude of an ear ring fastening and tapers around the ring, the smaller end extending from the ring and terminating in a needle point for piercing an ear lobe, said means thereby being adapted to pierce an ear lobe and insert the ring therein and to fill the pierced opening to any desired size during healing.

5. Means to facilitate forming an ear lobe piercing to desired size comprising an open ring, the material of which is of size of the order of magnitude of an ear ring fastening and tapers around the ring, the larger end being perforated, the smaller end extending from the ring and terminating in a needle point for piercing an ear lobe, the smaller end being bent to form a hook near its juncture with the body of the ring, whereby on removal of the needle end the hook may engage the perforation to close the ring, said means thereby being adapted to pierce an ear lobe and insert the ring therein and to fill the pierced opening with a closed ring to any desired size during healing.

20 6. Means to facilitate forming an ear lobe piercing to desired size comprising an open ring, the material of which is of size of the order of magnitude of an ear ring fastening and tapers around the ring uniformly throughout, the smaller end being bent near its juncture with the body of the ring and extending from the ring said extending portion near the ring being of size and form to be drawn after an ear-piercing needle through an ear lobe piercing and to lead the smaller end of the tapered ring through the piercing, whereby the smaller end may be pulled through a pierced opening in an ear lobe the larger end of the tapered ring being adapted to engage with the small bent end and said small end bent portion being sufficiently strong to hold the tapered ring together on engaging with the larger end of the ring.
